CLAIM

The ornamental design for a folded box blank with a removably attached lid blank, as shown and described.

DESCRIPTION

FIG. 1 is a front elevation view of a folded box blank with a removably attached lid blank;

FIG. 2 is a rear elevation view of the folded box blank with a removably attached lid blank of FIG. 1;

FIG. 3 is a top view;

FIG. 4 is a bottom view;

FIG. 5 is a left side view; and,

FIG. 6 is a right side view.

The broken lines shown on FIGS. 1 and 2 represent fold lines.
